UNITED STATES PATENT OFFICE

1,992,035

PIEZO ELECTRIC OSCILLATION GENERATOR

Harry R. Meahl, Schenectady, N. Y., assignor to
General Electric Company, a corporation of
New York

Application October 15, 1931, Serial No. 569,000

6 Claims. (Cl. 250—36)

My invention relates to oscillation generators of the type in which the frequency is controlled by means of a piezo electric device, such as a quartz crystal.

5 It has for one of its objects to provide an oscillation generator of the type indicated in which the frequency of oscillations produced is affected to a smaller degree by circuit adjustments and extraneous influences than has heretofore been
practicable.

A further object of my invention is to provide an oscillation generator of the type indicated which is characterized by improved constancy of frequency of oscillations produced and which at 15 the same time, when using an electron discharge device of a particular rating, is capable of producing a greater amount of high frequency energy in the output circuit than has heretofore been possible.

20 Still a further object of my invention is to provide a piezo electric oscillation generator utilizing a three electrode electron discharge device and in which extremely high anode voltage may be employed without subjecting the crystal to stresses likely to cause rupture thereof.

The novel features which I believe to be characteristic of my invention are set forth with particularity in the appended claims. My invention itself, however, both as to its organization and 30 method of operation, together with further objects and advantages thereof, may best be understood by reference to the following description taken in connection with the accompanying drawing in which Fig. 1 represents an embodiment of my invention and Fig. 2 represents a modification thereof.

Referring to the drawing, I have shown in Fig. 1 an electron discharge device having an anode 1, a grid 2, and a cathode 3. Between the grid and 40 cathode is connected a piezo electric device 4 in series with a tuned circuit comprising inductance 5 and a condenser 6. The piezo electric device is shunted by a resistance 7 in the usual way to afford a passage for the flow of grid current and 45 to establish a proper bias upon the grid. The inductance 5 of the tuned circuit comprises the secondary winding of a step down transformer the primary winding 8 of which is connected between the anode and cathode of the discharge 50 device in series with a source of anode potential 9. If desired, a choke coil 10 connected in series with the source 9 and a by-pass condenser 11 connected in shunt therewith may be employed to prevent the flow of high frequency currents in 55 the battery 9. Oscillations produced between the

anode and cathode of the discharge device may be supplied to any desired load circuit. In the drawing I have indicated by the rectangle 12 the amplification stages of an ordinary radio transmitter by means of which oscillations from the anode 1 are amplified and supplied to an antenna 13.

As thus far described the system of my invention is similar to that described in Fig. 3 of United States Patent No. 1,472,583 to Walter G. 10 Cady, issued October 30, 1923. I have found, however, that very pronounced improvements in the operation of the system may be effected by tuning the circuit 5, 6 to a frequency within a range of from one quarter to three quarters of 15 the crystal frequency and by so connecting the transformer 5, 8 that oscillations are supplied from the anode circuit to the grid circuit in degenerative phase; that is, in such phase that were the grid connected directly to the upper terminal of winding 5, or were the crystal 4 removed from the circuit, the system could not oscillate by virtue of the coupling between the anode and grid circuits. The electromotive force supplied to the grid circuit by the inductive effect between 20 windings 8 and 5 then opposes that supplied to the grid due to the inherent capacity effect existing between these windings and between the grid and anode of the discharge device, thereby leaving only a residual of energy transfer sufficient to support oscillations when the crystal is 25 in place.

It has been found that with the system as thus 30 adjusted oscillations of high power are produced in the output circuit having the natural frequency of the crystal and further that the frequency of these oscillations is unaffected by circuit adjustments over a very large range thereof. Thus, for example, the frequency remains 35 substantially constant over the range of adjustments of circuit 5, 6 for resonance at any frequency within the range between approximately one quarter to three quarters of the crystal frequency. With the circuit tuned within this 40 range I have found no condition under which the system will oscillate at any frequency other than the natural frequency of the crystal. If the tuning of the circuit be varied from the neighborhood of three quarters of the natural frequency 45 of the crystal toward the crystal frequency, oscillations cease until a point is reached at which the circuit is tuned to a frequency substantially equal to, or slightly higher than the crystal frequency where oscillations are again produced 50 55

over a narrow range of the circuit tuning. Beyond this range oscillations again cease.

It has heretofore been common practice in the construction of oscillation generators to tune the anode circuit to a fixed frequency, which may be equal to or slightly higher than the crystal frequency and to arrange the circuits so that the anode circuit is coupled to the grid circuit only by the inherent capacity existing between the grid and anode of the discharge device employed, the crystal being connected between the grid and cathode. As thus constructed the system operates solely by virtue of the inherent coupling between the anode and grid within the discharge device.

In the system of my invention, on the other hand, the oscillations are produced solely by virtue of the close coupling which exists between the coils 5 and 8. It has been found that if this coupling be removed, or winding 5 short-circuited, oscillations immediately cease. This is true even though the primary winding 8 has a natural period greater than the crystal frequency. The inherent capacity between the anode and grid of the system constructed in accordance with my invention has but slight effect in supporting operation of the system, and may be eliminated, as by the use of a discharge device of the screen grid type in which the screen grid is maintained at positive potential and is grounded by means of a condenser to the cathode, without adversely affecting the operation of the system. I have found, however, that a slightly different adjustment of coils 8 and 5 may be necessary when a screen grid tube is employed.

A further important advantage resulting from my invention resides in the fact that extremely high anode voltages may be employed without subjecting the crystal to stresses likely to cause rupture thereof. It has been customary in piezo electrically controlled electron discharge oscillators of the prior art to employ an anode voltage upon the discharge device which is a relatively small portion, as for example, less than half, of the maximum rated anode voltage of the discharge device. This was necessary in order to secure desired stability of operation of the system under control of the crystal and to protect the crystal against excessive stresses. It has been found, however, that with the circuit arranged as herein described a value of anode voltage approximately equal to or slightly less than the maximum rated anode voltage of the discharge device may be employed without reducing the stability beyond that which is obtainable from the best circuits of the prior art when using about one-half of the maximum rated anode voltage. For a specific example, when utilizing a particular discharge device known in the art as UX210 an anode voltage of four hundred volts may be utilized without subjecting the crystal to dangerous stress whereas when this discharge device is employed in the circuits of the prior art it is impractical to utilize a value of anode voltage in excess of approximately one-half of this amount.

For a test of my device under practical operating conditions it was connected to control the frequency of a high power broadcast transmitter operating in actual service at a frequency of 790 kilocycles. It was in continuous service for a period of about a month during which time the maximum frequency drift from normal which occurred was 7 cycles and the average frequency drift was 4.6 cycles. An oscillation generator of the fixed tuned anode type referred to above in

which the capacity between the grid and anode was relied upon for operation of the device employed in the transmitter and under the same operating conditions, including the same discharge device and the same values of operating voltages, for a period of a month produced a maximum frequency drift from normal of 90 cycles and a mean frequency drift of 35 cycles. In this test the anode voltage employed was of a value appropriate to the latter type of circuit. Even under this condition the output obtained from the circuit in accordance with my invention was approximately one and one-half times greater than that obtained from the prior art circuit during the entire period in which the system was in operation.

In Fig. 2 I have shown a modification of the arrangement shown in Fig. 1 whereby additional advantages are obtained. In this Figure I have shown a resistance 14 connected in series with the anode circuit of the discharge device and having a condenser 15 variably connected across a portion thereof thereby to permit of variation of the alternating current resistance of the plate circuit. This is desirable in the event that the impedance of the input to the transformer 8, 5, as due for example to distributed capacity in the winding 8, is low as compared with the anode impedance of the discharge device at the frequency at which the system operates. In this case the alternating current resistance of the anode circuit should be of such value as to cause the external impedance of the anode circuit approximately to match, or, in the case of a low impedance tube, to exceed, the internal anode impedance of the discharge device. In cases where the system is designed for operation at a single frequency the resistance 14 may be omitted and the coil 8, 5 designed to afford the desired impedance, but where the system is operated over a range of frequencies it is usually desirable that the resistance be employed to hold the impedance of the anode circuit up to a desired value at those frequencies where the impedance of the coil is too low for efficient operation of the discharge device.

This resistance has the effect of increasing the range of circuit adjustments over which desired operation of the device under control of the crystal may be had. It has been found that with resistance 14 properly adjusted oscillations having the frequency of the crystal are produced over a range of adjustment of the circuit 5, 6 for resonance at frequencies varying from one quarter of the crystal frequency to the crystal frequency and even slightly higher than the crystal frequency dependent upon the activity of the particular crystal used. The frequency at which the circuit 5, 6 is tuned for best operation of the system, however, varies somewhat with the natural frequency of the crystal. For example, a crystal having a natural frequency of 1928.75 kc. was found to produce best operation when the grid circuit was tuned to a frequency about 94% of the crystal frequency whereas a crystal having a natural frequency of 4750 kc. was found to produce best operation with the grid circuit tuned at about 72% of the crystal frequency. Crystals having intermediate natural frequencies were also found to produce best operation with the grid circuit tuned at intermediate percentages of the crystal frequency. Thus for best operation the percentage of the crystal frequency at which the circuit 5, 6 should be tuned decreases as the crystal frequency increases. At very low frequencies,

as for example, with a crystal of 100 kc. frequency the circuit 5, 6 may be tuned relatively close, as for example within 1 percent, to the crystal frequency. I attribute this result principally to the increasing effect of extraneous influences upon operation of the system at the higher frequencies and increased activity of high frequency crystals.

It will also be observed in Fig. 2 that the crystal 4 is connected between the tuned circuit 5, 6 and the cathode. This is important in that the crystal cell may be grounded thereby avoiding the necessity for insulation of the crystal cell from ground. Further the necessity for isolation of the cell from ground to avoid certain undesired capacity effects are avoided.

The resistance 7 in this figure is connected directly between the grid and cathode.

While I have shown a particular embodiment of my invention it will of course be understood that I do not wish to be limited thereto since different modifications in the arrangement employed may be made and I contemplate by the appended claims to cover any such modifications as fall within the true spirit and scope of my invention.

What I claim as new and desire to secure by Letters Patent of the United States, is:

1. The combination, in an oscillation generator, of an electron discharge device having a grid, an anode, and a cathode, a transformer having a primary winding connected between the anode and cathode, and a secondary winding connected between said grid and cathode, a piezo electric device connected in circuit with said grid and said secondary winding, said winding being so poled that the voltage on the terminal thereof connected to said grid is in degenerative phase when the piezo electric device is removed from said circuit, and means whereby said transformer is tuned to a frequency substantially lower than the natural frequency of said piezo electric device during the operation of said oscillation generator to produce oscillations having said natural frequency.
2. The combination, in an oscillation generator, of an electron discharge device having a grid, an anode and a cathode, means to cause said discharge device to produce oscillations, said means including circuit connections between the grid and cathode and anode and cathode, an inductive coupling between said circuit connections, a piezo electric device coupled with said circuit connections to control the frequency of said oscillations, and means includes said inductive coupling to reduce the reaction on said piezo electric device to such an extent that oscillations having the natural frequency of said piezo electric device are produced over a range of tuning of said circuit connections extending from the crystal frequency to a frequency less than half of the crystal frequency, and means to tune said circuit connections to a desired frequency in said range.
3. The combination, in an oscillation generator, of an electron discharge device, untuned anode and tuned grid circuits therefor, a coupling device included in said circuits to supply oscillations from the anode circuit to the grid circuit in degenerative phase, piezo electric means in series with the tuning element of said tuned grid circuit for causing said device to produce oscillations and an impedance connected in said anode circuit of such value that the total impedance of the anode circuit external of the discharge device approximately matches the internal impedance of the discharge device.
4. The combination, in an oscillation generator, of an electron discharge device having an anode, a cathode, and a grid, a tuned circuit and a piezo electric device connected in series between said cathode and grid, a source of electromotive force connected in circuit between said anode and cathode and an inductive coupling device having its input connected in circuit between said anode and cathode and its output connected in circuit between the grid and cathode, said coupling device being poled to supply oscillations from the anode circuit to said tuned circuit in degenerative phase and to protect said piezo electric device against the anode voltages whereby said source of electromotive force may have a value approaching the maximum rated anode voltage of said discharge device without endangering said piezo electric device.
5. The combination, in an oscillation generator, of an electron discharge device having a grid, an anode, and a cathode, a transformer having a primary winding connected between the anode and cathode, and a secondary winding connected between the grid and cathode and a piezo electric device connected in series circuit relation with said grid and said secondary winding, means to tune said secondary winding, the tuning of said grid circuit being determined by said means, said windings being so poled that the voltage induced in said secondary winding due to mutual inductance between said windings is supplied to said grid in opposition to the voltage supplied to said grid due to capacitive effects between said windings.
6. The combination, in an oscillation generator, of an electron discharge device having an anode circuit and a grid circuit, a transformer having an untuned primary winding connected in said anode circuit and a tuned secondary winding connected in said grid circuit, said windings being so poled that the electromotive force supplied to said grid circuit due to mutual inductance between said windings is opposed to electromotive force supplied to said grid due to capacitive effects between said windings, and a piezo electric device connected in series with said tuned secondary winding and said grid, said transformer being so proportioned that said electron discharge device is inoperative to produce oscillations except when said piezo electro device is connected to said grid

HARRY R. MEAHL.
